CLAIM

The ornamental design for a bottle, as shown and described.

DESCRIPTION

FIG. 1 is a top perspective view of a bottle.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a top perspective view of a bottle.

FIG. 10 is a bottom perspective view thereof.

FIG. 11 is a front view thereof.

FIG. 12 is a rear view thereof.

FIG. 13 is a left side view thereof.

FIG. 14 is a right side view thereof.

FIG. 15 is a top view thereof; and,

FIG. 16 is a bottom view thereof.

The dash-dash broken lines represent portions of the bottle
that form no part of the claimed design. The dash-dot broken
lines represent boundaries of the claimed design and form no
part of the claimed design. Any surfaces inside the bottle
form no part of the claimed design.
